US00D854029S

(12) **United States Design Patent** (10) **Patent No.:** **US D854,029 S**
(45) **Date of Patent:** **** Jul. 16, 2019**

(54) **DISPLAY SCREEN OR PORTION THEREOF
WITH GRAPHICAL USER INTERFACE**

(71) Applicant: **SIEMENS
AKTIENGESELLSCHAFT**, München
(DE)

(72) Inventors: **Stefan Hofmann**, München (DE); **Axel
Platz**, München (DE); **Sonja Sander**,
München (DE)

(73) Assignee: **SIEMENS
AKTIENGESELLSCHAFT**, München
(DE)

(**) Term: **15 Years**

(21) Appl. No.: **29/619,986**

(22) Filed: **Oct. 3, 2017**

(30) **Foreign Application Priority Data**

Apr. 4, 2017 (EM) 001458186

(51) **LOC (11) Cl.** **14-04**

(57) **CLAIM**

The ornamental design of a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen or portion thereof with graphical user interface showing our new design.

The broken line in the FIGURES shows a display screen or portion thereof, and forms no part of the claimed design.

**1 Claim, 1 Drawing Sheet
(1 of 1 Drawing Sheet(s) Filed in Color)**
